UNITED STATES PATENT OFFICE.

ENOCH P. STEVENS, OF CHICAGO, ILLINOIS; MARY ANN STEVENS EXECUTRIX OF
SAID ENOCH P. STEVENS, DECEASED.

KILN CONSTRUCTION.

Application filed November 16, 1922. Serial No. 601,206.

To all whom it may concern:

Be it known that I, ENOCH P. STEVENS, a citizen of the United States, residing at Chicago, in the county of Cook and State 5 of Illinois, have invented certain new and useful Improvements in Kiln Constructions, of which the following is a specification.

The present invention relates to kiln construction.

10 An object of the present invention is to provide a kiln in which the distribution of heat may be readily controlled.

A further object is to provide a kiln of 15 novel construction involving means for conducting air in proximity to heated parts of the kiln and whereby the operation of said kiln may be conveniently controlled.

A further object is to provide a kiln 20 having means for supplying products of combustion and means for efficiently pre-heating air for mixture with said products of combustion, said kiln being readily controllable for distributing the heat and so constructed that cleaning and repairs may 25 be accomplished without shutting down the kiln.

A further object is to provide a kiln with 30 improved combustion means whereby repairs and cleaning of the fire box may be accomplished without shutting down the kiln.

Further objects will appear as the description proceeds.

Referring to the drawings:—

35 Figure 1 is a sectional view of a kiln embodying the principles of the present invention;

Figure 2 is a sectional view taken on the 40 plane indicated by the arrows 2—2 of Figure 1;

Figure 3 is a sectional view taken on the plane indicated by the arrows 3—3 of Figure 1.

The numeral 1 indicates the wall of a 45 kiln, which wall may be of circular construction, said wall 1 being surmounted by the dome 2. Placed preferably centrally of the wall 1 is the flue 3, which comprises an upstanding cylindrical member having 50 co-axial walls 4 and 5. The inner wall 4

provides a passageway for products of combustion and the walls 4 and 5 provide between them an annular space 6 for air. The wall 5 is provided with apertures 7—7 near the top of said wall, which apertures 55 may be spaced around the circumference of wall 5 and should preferably be inclined to the vertical, whereby air under pressure may be projected through said apertures at an angle between the vertical and horizontal. 60 The walls 4 and 5 should preferably be connected at their upper portions, whereby air will be constrained to pass through the inclined passageways 7—7. The flue 3 is provided with a horizontal baffle wall 8, 65 which directs products of combustion laterally of the kiln.

The kiln is provided with a floor 9, which 70 may be provided with apertures permitting the escape of gases therethrough. Mounted beneath said floor 9 is the baffle wall 10 for directing gases toward the periphery of the kiln, whereby to aid in the even distribution of the heat within the kiln. Below the baffle wall 10 are a number of passageways, 75 one of which is indicated by the numeral 11, which communicate with the stack tunnel 12.

Leading to the flue 3 is a conduit 13 which 80 forms a passageway 14 for gases produced in the fire box 15. A substantially level surface of fuel in the fire box 15 may be maintained by means of the push rod 16, which may be operated at intervals by the gearing 17, which may be driven in any 85 preferred way. The numeral 18 indicates a supply of fuel from which delivery may be made as desired. The conduit 13 also provides passageways 19—19 communicating with the annular space 6 in the flue 3. Said 90

passageways 19—19 carry air to said annular space 6 from the opening 20. By reason of the fact that the passageways 19—19 are arranged in proximity to the passageway 14 and heated gases passing therethrough, said 95 air will be preheated, whereby a high temperature may be maintained within the kiln.

The fire box 15 is provided with a grate 21 of any preferred construction. According to the present invention, air is admitted 100

in distinct passageways to different sections of said grate, said passageways extending from front to rear of the grate. In the illustrated embodiment of the present invention the ash pit 22 below the grate is divided into a plurality of compartments 23-23 by the partition walls 24-24. Said partition walls 24-24 extend in a direction from front to back of the grate 21 and their upper portions should be in proximity to the under side of said grate 21.

The numeral 25 indicates an air duct through which air may be conducted in proximity to the kiln for the purpose of heating said air. Air in duct 25 will preferably be under pressure and will be connected to the various compartments 23-23 below the grate 21. One method of distributing the air into the compartments 23-23 is illustrated in the drawing. A header 26 may be provided from which branch pipes 27-27 lead to the individual compartments 23, each of the branch pipes being individually controlled, as, for example, by a valve 28. The header 26 communicates with the duct 25 through a connection 29, a fragment of which is illustrated in Figure 2. Air for the opening 20 and passageways 19 may be taken from the header 26, a suitable valve 26' being provided for controlling the pressure of the air in said passages 19-19 and apertures 7-7 of the flue 3.

In operation, the push rod 16 will be operated at intervals to maintain a substantial level of fuel in the fire box 15. Air for the kiln will pass through duct 25, being heated due to its proximity to the kiln, and will pass through connection 29, header 26 and branch pipes 27-27 to the various compartments 23-23. The air entering said compartments will support combustion in the fire box 15 and gases will pass through passageway 14 to the flue 3, striking the baffle plate 8, where said gases will be deflected laterally. Air under pressure will pass through the passageways 19-19 of the conduit 13 to the annular space 6 in the flue 3, issuing from said space 6 through the apertures 7-7 in a direction inclined to the vertical. Said air will project the gases from flue 3 toward the top and toward the cylindrical wall of the kiln. By controlling the pressure in the passageways 19 and annular space 6, the force with which the air and gases are projected from the flue may be controlled. By means of this control the distribution of the heat within the kiln may be accomplished with improved uniformity.

By reason of the distribution of air from duct 25 to the various compartments 23-23 under the grate 21, it is possible to control, individually, the air supply to the various sections of the grate. If it should be found necessary or desirable to repair or clean any of said sections of the fire or grate, the sup-

ply of air may be shut off from the corresponding compartment and the fire drawn from that section of the grate, whereby the repairs or cleaning may be made without drawing the fire from the remainder of the 70 grate.

The importance of this feature from a practical standpoint may be explained as follows: It is desirable to attain and maintain a certain predetermined temperature 75 within the kiln. Due to imperfect fuel or other factors, the fire is very likely to become fouled with clinkers or other objectionable matter. In order to clean the fire, it has been necessary in prior practice to draw the 80 fire in the fire box, thereby allowing the temperature in the kiln to drop several hundred degrees. After the fire has been cleaned, a long period of time, amounting to many hours, is required to bring the 85 temperature of the kiln back to the required operating temperature. According to this prior practice, many hours of time and labor are lost and, in addition, a great amount of fuel is consumed in bringing the temperature back from the reduced temperature to the necessary operating temperature. According to the present invention, however, the air supply to one of the compartments 90 may be shut off and the fire in that section of the grate drawn and cleaned, the other sections being kept in operation to maintain the temperature in the kiln at the desired degree. The section of the fire above each compartment may be cleaned in this 95 way without allowing the temperature to drop a material amount. Time, labor and fuel are all conserved to a very material extent.

A further advantage of the present invention lies in the fact that a better control may be had within the kiln during the process of drying, or water-smoking, the green brick. When the green brick are placed in the kiln they will ordinarily contain an excess of 100 moisture, which moisture should be driven off at a relatively low temperature. Too high a temperature at this stage is destructive to the green brick. According to the present invention, during the early stages 105 of the brick treatment fire may be maintained in less than all of the sections above the chambers 23-23, and air under pressure will be passed through the other sections, whereby a strong draft is maintained, though the temperature in the kiln is kept at a point below that which will be destructive to green brick. The strong draft will drive off the moisture from the green brick, leaving said brick in condition to receive the high temperatures required for the complete heat treatment.

One embodiment of the present invention has been described in detail. Many modifications will occur to those skilled in the art. 130

It is intended in this patent to cover all such modifications that fall within the scope of the invention as defined by the appended claims.

5 I claim:

1. A kiln, comprising an upstanding flue providing a chamber for the passage of gases and a space surrounding said chamber for the passage of air, said flue being provided with means for directing said gases horizontally and means for directing said air at an angle inclined to the vertical. 70
- 10 2. A kiln, comprising a flue having concentric walls, the inner of said walls providing a space for the passage of gases, said walls providing between them a space for the passage of air, the outer wall being provided with apertures for deflecting air at an angle inclined to the vertical. 75
- 15 3. A kiln, comprising a cylindrical chamber, an upstanding flue located within said chamber centrally thereof, means for conducting heated gases to said flue and for discharging same into said chamber, said flue having means providing a passageway for air, said last mentioned means being provided with apertures for directing said air at an angle inclined to the vertical. 80
- 20 4. A kiln, comprising a cylindrical chamber, an upstanding flue located therein, said flue having a central passageway and an annular passageway separated from but surrounding said central passageway, a conduit forming a passageway for conducting gases to said central passageway, said conduit having another passageway leading to said annular passageway, and means for controlling the pressure of air in said annular passageway. 85
- 25 5. A kiln, comprising a cylindrical chamber, an upstanding flue located therein, said flue having a central passageway and an annular passageway separated from but surrounding said central passageway, a conduit for conducting gases to said central passageway, said conduit having another passageway leading to said annular passageway, and means for controlling the pressure of air in said annular passageway. 90
- 30 6. Kiln construction, comprising a heating chamber, a fire box for producing gases for said chamber, said fire box being provided with a grate, means for conducting air to the space below said grate, means dividing said space into a plurality of compartments divided along lines extending from front to rear of the grate, said conducting means comprising a plurality of independently controllable conduits. 95
- 35 7. Kiln construction, comprising a heating chamber, a fire box for producing gases for said heating chamber, said fire box hav- 100
- 40 ing a grate, walls extending from front to rear of said grate, said walls forming compartments for conducting air to sections of said grate, and conduits for leading air individually to said compartments, said conduits being independently controlled. 105
- 45 8. A kiln comprising an upstanding flue providing a chamber for the passage of gases and a space surrounding said chamber for the passage of air, a fire box, and a conduit for directing gases from said fire box to said chamber, means being provided for conducting air to said space, an air duct thermally associated with said kiln whereby air in said duct may be heated by heat conduction from said kiln, said conduit and conducting means having communication with said air duct, and means for selectively controlling the supply of air from said air duct to said conduit and said conducting means. 110
- 50 9. A kiln comprising a cylindrical chamber, an upstanding flue located therein, said flue having a central passageway and an annular passageway separated from but surrounding said central passageway, a conduit for conducting gases to said central passageway, said conduit having another passageway leading to said annular passageway, an air duct in thermal association with said chamber whereby air in said air duct is heated by conduction from said chamber, said air duct having communication with said conduit and said other passageway, and means for individually controlling the passage of air from said air duct to said conduit and said other passageway. 115
- 55 10. A kiln comprising a grate having a plurality of independently controlled sections, a cylindrical chamber, an upstanding flue located therein, said flue having a central passageway and an annular passageway separated from but surrounding said central passageway, a conduit for conducting gases from said grate to said central passageway, said conduit having another passageway leading to said annular passageway, an air duct thermally associated with said chamber whereby air in said duct is heated by conduction from said chamber, means for controlling the pressure of air in said other passageway, and means for controlling the pressure of air in said conduit, said last mentioned means including individually controllable air inlet means for the various sections of said grate. 120
- 60 11. A kiln construction comprising a heating chamber, a fire box for producing gases for said chamber, said fire box being provided with a grate, means for conducting air to the space below said grate, means dividing said space into a plurality of compartments divided along lines extending from front to rear of the grate, said heating chamber being provided with a flue hav- 125
- 65 12. Kiln construction, comprising a heating chamber, a fire box for producing gases for said heating chamber, said fire box hav- 130

ing a central passageway communicating with said fire box and having another passageway in thermal association with said central passageway, an air duct for supplying air to said conducting means, said air duct having communication with said other passageway, and means for controlling the

pressure of the air supplied from said air duct to said conducting means and to said other passageway.

Signed at Chicago, Illinois, this 13th day of November, 1922:

ENOCH P. STEVENS.
